UNITED STATES PATENT OFFICE

FRANK G. BROTHZ, OF KOHLER, WISCONSIN

DESIGN FOR A FAUCET

Application filed May 12, 1932. Serial No. 43,775. Term of patent 14 years.

To all whom it may concern:

Be it known that I, FRANK G. BROTHZ, a citizen of the United States, residing at Kohler, in the county of Sheboygan and State of Wisconsin, have invented a new, original, and ornamental Design for a Faucet, of which the following is a specification, reference being had to the accompanying drawing forming part thereof. Figure 1 is a perspective view of the article showing my new design, and Fig. 2 is a plan view thereof showing my new design.

I claim:

The ornamental design for a faucet as shown.

FRANK G. BROTHZ.
